CAN OPENER

Frank B. Roth, Clayton, Mo., assignor to Swing-A-Way Manufacturing Company, St. Louis, Mo., a corporation of Missouri

Application January 17, 1955, Serial No. 34,015

Term of patent 14 years

(Cl. D22—2)

Figure 1 is a side elevational view of a can opener, showing my new design;

Figure 2 is a bottom plan view thereof;

Figure 3 is an elevational view showing the side opposite to Figure 1;

Figure 4 is an enlarged fragmentary side elevational view showing in detail the grooved ornamentation which constitutes the characteristic feature of my design; and

Figure 5 is a cross-sectional view taken on the line 5—5 of Figure 4.

The essential features of my design reside in the portions shown in solid lines on the drawing. The operating lever, support, and the other operating parts shown in broken lines in Figure 1 have been omitted from the other figures for convenience of illustration.

I claim:

The ornamental design for a can opener, as shown and described.
